MAGNIFYING DEVICE

Robert Dwight Lynch, 3520 5th Ave.,
Los Angeles, Calif. 90018

Filed Dec. 29, 1969, Ser. No. 20,681

Term of patent 14 years

Int. Cl. D16—08

U.S. Cl. D57—1

FIG. 5

FIG. 1 is a perspective view of a magnifying device embodying my new design;

FIG. 2 is a left side elevational view of the magnifying device shown in FIG. 1;

FIG. 3 is a front elevational view of the magnifying device shown in FIG. 1 in which the cylindrical member is shown in a raised position;

FIG. 4 is a right side elevational view of the magnifying device shown in FIG. 3; and

FIG. 5 is a top plan view of the magnifying device shown in FIG. 3.

I claim:

The ornamental design for a magnifying device, as shown and described.
